SAND BAILER

Martin F. Rogers and Lloyd T. Mann,
Seven Sisters, Tex.

Application July 18, 1941, Serial No. 402,974

4 Claims. (Cl. 166—19)

This invention relates to a bailer and has particular relation to a tool of the character described particularly useful for bailing sand from wells.

An object of the invention is to provide a bailer of the character described which is adapted to be let down into the well by a wire line and manipulated therein to pump a load of sand into the bailer and then be withdrawn to the ground surface for unloading.

In one form of the invention fluid under pressure may be entrapped within the tool and utilized at the ground surface for discharging the load from the bailer.

Another object of the invention is to provide in a bailer of the character described novel entrapping means for entrapping a load of sand or other detritus as well as for entrapping a charge of fluid under pressure to be later utilized at the ground surface for discharging the load.

With the above and other objects in view the invention has particular relation to certain novel features of construction, operation and arrangement of parts, examples of which are given in this specification and illustrated in the accompanying drawing, wherein:

Figure 1 shows a vertical, sectional view of the bailer.

Figure 2 shows a cross-sectional view taken on the line 2—2 of Figure 1.

Figure 3 shows a vertical, sectional, view of the lower end of the barrel showing the unloading valve in open position, and

Figure 4 shows a side elevation, partly in section, of another embodiment of the bailer.

Referring now more particularly to the drawing wherein like numerals of reference designate the same parts in each of the figures, the numeral 1 designates the barrel. In the present illustration, it is shown formed of two sections screwed together. The lower end of the barrel has a side discharge opening 2 which is normally closed by an inside sleeve valve 3. This sleeve valve is normally held in closed position by means of a pin or stud 4 projecting outwardly from said valve and seated in the laterally turned end of the inverted J-slot 5.

The sleeve valve is held against disengagement from the barrel by the interengaging flanges 6, 7, the former of which is an external flange on the upper end of the valve 3 and the latter of which is an inwardly extended flange on the lower end of the barrel 1 beneath the opening 2.

The lower end of the sleeve valve 3 has an

inlet opening 8 which is controlled by an upwardly opening flap valve.

Fitted over the upper end of the barrel there is a cylinder 10 whose lower end is in sealed engagement with the barrel. The upper end of this cylinder is closed by the hollow head 11 to the upper end of which a wire line may be attached for lowering the bailer into the well.

Screwed into the cylinder 10 beneath the head 11 there is a plug 11a and attached to and depending from this plug there is a valve stem 12 to the lower end of which the upwardly tapering valve 13 is secured which cooperates with the tapering seat 14 in the upper end of the barrel.

When the bailer lands on bottom the cylinder may be reciprocated up and down so as to draw a load of sand into the barrel past the valve 12, the liquid and air above the valve 13 being pumped out through the duct 15 of the plug 11a past the upwardly opening ball valve 16 and out through the ducts 17 of the head 11.

The valve 16 cooperates with an annular valve seat 18 having an external annular flange which is clamped between the head 11 and the plug 11a.

When the barrel is filled with sand it may be withdrawn to the ground surface and the sleeve valve 3 turned to carry the stud 4 out of the laterally turned end of the J-slot 5 thus permitting the sleeve valve 3 to drop down to open the discharge port 2 so as to allow the load of sand to escape from the barrel 1.

A coil spring 19, around the barrel 1 and seated on the lower section thereof acts as a bumper during the reciprocation of the barrel 10. In the embodiment illustrated in Figure 4 a disc 20 is substituted for the valve seat 18 to prevent the escape of any fluid under pressure.

In this form there is an annular stop 21 secured on the upper section of the barrel 1 and interposed between this stop and the lower end of the cylinder 10 there is a coil spring 22.

This form of the bailer may be used where there is high pressure in the well. When it is lowered into the well the valve 13, Figure 4, is held closed by the spring 22 and when it lands on bottom the cylinder 10 may be lowered to cause the valve 13 to open and the pressure in the well will force the sand into the barrel 1, the gas under pressure entering into the cylinder 10 above.

Upon elevating this form of the bailer to the ground surface the valve 13 will be first closed to trap said gas under pressure and will be held

closed by the spring 22 and the sand and water will fill the barrel 1.

When the bailer is withdrawn to the ground surface the sleeve valve 3 may be opened, as above, to open the discharge port 2 and the cylinder 10 may then be forced downwardly to open the valve 13 and the pressure in the cylinder will operate to discharge the contents of the barrel 1 through the opening 2.

The drawing and description are illustrative merely while the broad principle of the invention will be defined by the appended claims.

What we claim is:

1. A bailer for wells comprising a tubular barrel for the reception of material from the well and having an unloading opening, and an unloading valve controlling said opening, an inlet valve at the lower end of the barrel for entrapping said material, means normally holding the unloading valve in position to close said opening and releasable to allow the unloading valve to move to open position, a cylinder reciprocable on the barrel, said barrel being provided with a valve seat, a stem attached to the cylinder and extended into the barrel, a pressure retaining valve on the stem and arranged to engage and disengage the valve seat for controlling communication between the interior of the barrel and cylinder, said cylinder having a chamber around the stem for the reception of fluid under pressure from the well available to effect discharge of the load in the barrel when the unloading valve is opened and said pressure retaining valve is moved away from its seat.

2. A bailer for wells comprising a tubular barrel whose upper end is provided with an upwardly converging seat, a cylinder reciprocable on the barrel and having a chamber for the reception of fluid from the barrel, a valve rod con-

nected to the cylinder at its upper end and whose lower end is extended into the barrel and formed into a valve adapted to contact and close said seat when the cylinder is in its upper position and to open the seat when the cylinder is in its lower position to allow fluid to flow from the barrel into the cylinder around said rod.

3. A bailer for wells comprising a tubular barrel whose upper end is provided with an upwardly converging seat, a cylinder reciprocable on the barrel and having a chamber for the reception of fluid from the barrel, a valve rod connected to the cylinder at its upper end and whose lower end is extended into the barrel and formed into a valve adapted to contact and close said seat when the cylinder is in its upper position and to open the seat when the cylinder is in its lower position to allow fluid to flow from the barrel into the cylinder around said rod, said cylinder having a valve controlled outlet passageway permitting escape of fluid from said chamber.

4. A bailer for wells comprising a tubular barrel whose upper end is provided with an upwardly converging seat, a cylinder reciprocable on the barrel and having a chamber for the reception of fluid from the barrel, a valve rod connected to the cylinder at its upper end and whose lower end is extended into the barrel and formed into a valve adapted to contact and close said seat when the cylinder is in its upper position and to open the seat when the cylinder is in its lower position to allow fluid to flow from the barrel into the cylinder around said rod and yieldable means on the barrel arranged to be compressed by the cylinder when the latter is moved to its lower position.
